US00D515034S

(12) **United States Design Patent** (10) Patent No.: **US D515,034 S**
(45) Date of Patent: **** Feb. 14, 2006**

(54) **MODULAR SYSTEM SUBSTATION**

(75) Inventors: **Chris Petrick**, Oak Park, IL (US);
David James Gennrich, Madison, WI (US); **Kent Bradley Chase**, Madison, WI (US); **Richard A. Nelipovich**, Madison, WI (US); **William Charles Lindeman**, Marshall, WI (US)

(73) Assignee: **Bretford Manufacturing, Inc.**,
Franklin Park, IL (US)

(**) Term: **14 Years**

(21) Appl. No.: **29/191,672**

(22) Filed: **Oct. 10, 2003**

(51) LOC (8) Cl. **13-03**

(52) U.S. Cl. **D13/139.4**

(58) Field of Classification Search **D13/137.2, D13/139.1, 139.4, 139.5, 139.6, 152, 184; 439/131, 535; 174/53**

See application file for complete search history.

(57) **CLAIM**

The ornamental design for a modular system substation, as shown and described.

DESCRIPTION

FIG. 1 is a perspective view of the modular system substation;

FIG. 2 is a front elevational view thereof;

FIG. 3 is a rear elevational view thereof;

FIG. 4 is a left side elevational view thereof;

FIG. 5 is a right side elevational view thereof; and,
FIG. 6 is a top view thereof, the bottom being unadorned.
The phantom line showing of environment is for illustrative purposes only.
